UNITED STATES PATENT OFFICE.

OTTO P. SCHUSTER, OF NORTH IRWIN, PENNSYLVANIA, ASSIGNOR TO WESTINGHOUSE ELECTRIC & MANUFACTURING COMPANY, A CORPORATION OF PENNSYLVANIA.

CONTACT FINGER.

Application filed August 7, 1928. Serial No. 127,731.

My invention relates to contact fingers primarily designed for use in controllers.

The object of my invention, generally stated, is the provision of an adjustable contact finger that shall be simple and efficient in operation and capable of being readily and economically manufactured.

A more specific object of my invention is to facilitate the taking apart of the contact finger to permit the removal and replacement of the parts subject to the greatest wear.

Another object of my invention is to provide for retaining the adjusting means in any position in which it may be set to space the contact-carrying member and the base member in order to tension the spring.

Other objects of the invention will, in part, be obvious and, in part, will appear hereinafter.

The invention accordingly is disclosed in the embodiment thereof shown in the accompanying drawing and comprises the features of structure, combination of elements and arrangement of parts which will be exemplified in the construction hereinafter set forth and the scope of the application of which will be indicated in the claims.

For a fuller understanding of the nature and objects of the invention, reference should be had to the following detailed description taken in connection with the accompanying drawing, in which:

Fig. 1 is a view, in side elevation, showing one embodiment of a contact finger constructed in accordance with this invention;

Fig. 2 is a view, partly in side elevation and partly in section, showing the relation of the operating parts of the contact finger;

Fig. 3 is a top plan view of the contact finger;

Fig. 4 is a sectional view taken along the line IV-IV of Fig. 2;

Fig. 5 is a view, in side elevation, of the resilient means provided for retaining the contact member in position on the base; and

Fig. 6 is a bottom plan view of the device shown in Fig. 5.

Referring now to the drawing, the reference character 10 designates generally the base of a contact finger provided with an inclined end portion 11 which is adapted for fastening to a board or any other support usually provided in controllers or the like for carrying contact fingers. As illustrated, the

member 11 has an opening 12 drilled therein near its end for the reception of a bolt 13 that may be used for attaching it to a support.

As shown, a substantially straight member 14 constitutes the main portion of the base member 10. In order to adapt the member 14 for the mounting of the contact-carrying member, shown generally at 15, an opening 16 is provided therein near the juncture of the two sections 11 and 14 of the base. Further, a slot 17 is cut in the free end of the straight section of the base 10 for the reception of the outer end of the contact-carrying member 15.

The contact-carrying member 15 comprises a main body portion 18, which is substantially straight, and two depending end portions 19 and 20. As will be observed by reference to Figures 1 to 4, inclusive, the depending end 19 is provided with a small projection or tongue 21 that is shaped to fit into the opening 16 in the base 10, and the member 20 is made narrow enough to fit into the slot 17.

Hence, by the insertion of the projection 21 into the opening 16, and the depending end portion 20 in the slot 17, the contact-carrying member 15 may be pivotally mounted on the base 10. Further, the depending end 20 will serve to guide the movement of the contact-carrying member 15 within predetermined limits.

As illustrated in Fig. 3, the lower end 22 of the depending member 19 is curved to permit lateral oscillatory movement of the contact-carrying member on the base. The oscillatory movement of the contact-carrying member 15 is not limited by the depending member 20, since the latter may be loosely mounted in the slot 17.

In order to retain the contact-carrying member 15 in position on the base 10, a resilient unit is utilized. The construction of the latter is best illustrated in Fig. 5 which shows it to comprise a pin 23 on which a spring 24 is mounted. The spring is retained in position on the pin by means of two slidably mounted dish-shaped washers 25 and 26. A head 27 is provided on the upper end of the pin, while the lower end is flattened, as shown at 28, so that the washers 25 and 26 cannot be removed. The flattened end 28 has another function which will be described hereinafter.

Since the object of this invention is to fa-

cilitate the tearing down of the contact finger for the replacement of parts, the resilient means for retaining the contact-carrying member 15 in position on the base is removably mounted, so that it may be detached at will. It will be readily understood that many methods may be adopted for removably mounting the pin on the base. In this particular construction, the intermediate member 14 of the base is crimped to provide a substantially inverted-V-shaped section 29, and a slot 30 extending longitudinally of the member 14 is punched therein for the reception of the end 28 of the pin 23.

15 When the head 28 of the pin is inserted through the slot 30 and turned through an angle of 90°, the shoulders 31 of the pin will seat in the crimped section 29. Since the spring 24 is in tension, it will serve to retain 20 the head of the pin 23 in position. In this manner, the pin is mounted to permit a certain oscillatory movement in every direction to allow the contact-carrying member to take different positions.

25 In order to adjust the contact-carrying member 15 relative to the base 10, a set screw 32 is mounted in the former. As will be observed, any adjustment of the set screw will vary the tension of the spring 24. The head 30 of the set screw 32 is made polygonal in shape, and a flat spring 33 is provided with a vertical section 34, which seats against the head of the set screw, is mounted on portion 20 of the contact-carrying member 15. The spring 33 35 will serve to retain the set screw in any position to which it may be rotated.

A contact member or tip 35 is mounted on an extension 36 of the depending member 20. As shown, the contact member 35 is provided 40 with a shoulder 37 which abuts against the end of the contact-carrying member. In forming the contact member 35, a stud 38 is provided thereon to serve in attaching it to the contact-carrying member. In this particular construction, the stud is also used for mounting the spring 33 on the contact-carrying member.

45 The contact member 35 is preferably made from some conducting material, such as copper or brass, but it may also be made from steel. With a view of establishing a good electrical connection between terminal and the contact member 35, a flexible laminated conductor 39 is provided, one end being 50 clamped between portion 36 of the contact-carrying member and the contact member 35.

55 After the contact finger is mounted on a supporting rail or the like, the set-screw 32 may be adjusted to properly tension the spring 24. In this manner, the proper pressure between the contacting surfaces may be obtained.

Assuming that the drum contact segment that engages the finger is uneven, the contact-carrying member 15 will oscillate about a

longitudinal axis to permit the contact member 35 to properly set or adjust itself to make engagement throughout the length of its contacting face. Accordingly, a contact finger of this type will readily adjust itself during operation over uneven surfaces and the like. 70

In order to tear down the contact finger, the pin 23 is disengaged from the base 10 by pressing down and turning. The contact-carrier 15 may then be removed. If the contact member 35 has been so worn as to require replacement, it can be readily detached by use of a file. Since the contact member 35 is made from copper, brass or some such material, little difficulty is experienced in 80 filing off the riveted end of the stud 38. In such constructions, a riveted stud is preferably for securing the contact tip 35, since a bolt and nut connection is unsuitable, because of its tendency to loosen with the continual working of the contact finger.

In setting the contact finger for operation, the set-screw 32 is adjusted to properly space the contact carrier 15 from the base 10 and to 90 position the contact member 35 to ride on the cooperating drum segment. If the drum segment has any raised portions, the contact carrier 15 may oscillate freely about a longitudinal axis extending through its inner end, while the spring 24 continuously urges the contact member 35 toward the drum segment. 95

Since certain changes may be made in the above construction, and different embodiments of the invention may be made without departing from the scope thereof, it is intended that all matter contained in the above description or shown in the accompanying drawing shall be interpreted as illustrative and not in a limiting sense. 100

I claim as my invention:

1. In a contact finger, in combination, a base member, a contact-carrying member pivotally mounted on the base member, resilient means for retaining the contact-carrying member in position on the base member, said contact-carrying member having an opening in its outer end, a contact member having a stud formed thereon, mounted on the contact-carrying member, the stud projecting through the opening and a shoulder formed on the contact member and disposed to engage the end of the contact-carrying member to retain the contact member in a predetermined position. 110

2. In a contact finger, in combination, a base member, a contact-carrying member pivotally mounted on the base member, resilient means for retaining the contact member in position on the base member, said contact-carrying member having an opening in its outer end, means for adjusting the contact-carrying member relative to the base member, a spring member mounted on the contact-carrying member for retaining the adjusting means in a predetermined position, a contact 120

105

115

125

130

member provided with a stud mounted on the contact-carrying member, the stud projecting through said opening, said stud being utilized to attach the spring member to the contact-carrying member.

3. In a contact finger, in combination, a base member, a contact-carrying member pivotally mounted on the base member, said contact-carrying member having an opening in its outer end, resilient means adapted to be removably mounted in the base member for retaining the contact-carrying member in position on the base member, a set screw for adjusting the contact-carrying member relative to the base member, a spring mounted on the contact-carrying member for retaining said set screw in position, a contact member provided with a stud mounted on the contact-carrying member, said stud projecting through the opening in the contact-carrying member and engaging the spring to retain the latter in position, a shoulder provided on the contact member, said shoulder being disposed to engage the end of the contact-carrying member to retain the contact member in a predetermined position.

4. In a contact finger, in combination a

base member, a contact-carrying member pivotally mounted on the base member, resilient means adapted to be removably mounted in the base member for retaining the contact-carrying member in position on the base member, a set screw mounted in the contact member and disposed to engage the base member whereby said members may be set in any predetermined relative positions, a spring carried by the contact-carrying member for retaining the set screw in position, a flexible conductor extending from the inner end of the base member to the outer end of the contact-carrying member, a contact member provided with a stud, said flexible conductor, contact-carrying member and spring being provided with aligned openings, whereby said stud may be utilized to retain said members together and a shoulder formed on the outer end of the contact member for engaging the end of the contact-carrying member, thereby to retain the stud in a predetermined position.

In testimony whereof, I have hereunto subscribed my name this 5th day of August, 1926.

OTTO P. SCHUSTER.
